8 Claims. (Cl. 280—51)

The present invention relates to delayed action power switches which respond to operation of a control to effect a delayed opening of a power circuit.

A power switch of this character can provide in a number of environments distinct advantages in the control of electric lights, for example. When installed in a bedroom, such a switch can permit a user to move a switch control to an "off" position and then make his way into bed before the switch operates to turn out the light. When installed to control an outside light for a residence or other building, such a switch permits a person to move a switch control to its "off" position before leaving the building and then proceed away from the building before the switch turns out the light. By keeping a controlled light burning for a limited period of time after the switch has been manually operated to turn out the light, such a switch enables the user to avoid the hazard and inconvenience of having to move away from the switch in the dark after the switch control has been operated.

However, prior switches of this character have tended to be impractical because of structural complexity, high manufacturing costs, lack of dependability, bulkiness, and other factors which have detracted from the advantages which may be gained from use of the switches.

One object of the invention is to provide a new and improved delayed action power switch well adapted for general residential and similar usages, and having an inherent practicality by virtue of being well adapted for economical manufacture and having an inherent capability of operating dependably and efficiently in service.

Another object is to provide a delayed action power switch as recited in the preceding object which occupies a very small space.

Another object is to provide a novel switch connector plug of small size adapted to be plugged into an ordinary household power outlet socket in the manner of a conventional electrical plug and serving to provide an efficient, dependable delayed action opening of the electrical circuit through the switched connector plug itself.

Another object is to provide a compact switch coupling adapted to couple an ordinary electrical plug to an ordinary electrical socket, and having an extremely economical construction which provides response to operation of a manual control on the coupling to provide an efficient and dependable delayed action opening of the circuit through the coupling in the manner described in relation to the preceding objects.

Another object is to achieve the objects previously recited by means of structure in which the working parts which effect the delayed opening of a circuit are confined essentially to a simple bimetallic element.

Other objects and advantages will become apparent from the following description of the exemplary forms of the invention illustrated in the drawings, in which:

FIGURE 1 is a perspective view illustrating in a somewhat exploded form the relationship to a plug and a socket of a delayed action switch coupling constructed in accordance with the invention;

FIG. 2 is a horizontal sectional view of the coupling taken generally with reference to the line 2—2 of FIG. 1;

FIG. 3 is a vertical sectional view taken along the line 3—3 of FIG. 2;

FIG. 4 is a simplified sectional view taken along the irregular line 4—4 of FIG. 2;

FIG. 5 is an exploded perspective view of the switch

2

operator and internal switching elements used in the coupling;

FIG. 6 is a perspective view showing the relationship to a power socket of a switched plug constituting a modified form of the invention;

FIG. 7 is a sectional view taken along the line 7—7 of FIG. 6;

FIG. 8 is a partially sectioned elevational view of a switched plug forming another modified embodiment of the invention; and

FIG. 9 is a sectional view taken along the line 9—9 of FIG. 8.

Referring to the drawings in greater detail, the plug-socket switch or coupling 10 forming the exemplary embodiment of the invention illustrated in FIGS. 1 to 5 comprises a housing 12 formed basically in two parts, a hollow plastic dome 14 defining a generally circular opening 16 into the dome, and a substantially flat circular floor 18 formed of an insulating material and adapted to fit into and close the opening 16 into the dome 14.

An electrical socket 20 adapted to receive a conventional electrical plug 22, FIG. 1, is integrally formed with the dome 14 on one side of the dome and defines two electrical socket openings 24 adapted to receive two parallel prongs 26 of a conventional connector plug 22.

Two socket output conductors 28, 29 disposed within the housing 12 are supported by two pins 30, 31 anchored to the floor 18. The output conductors 28, 29 extend from the spaced pins 30, 31 toward the inner ends 30 of the socket openings 24 and terminate in two upstanding wiper ears 32, 33 positioned in inward alinement with the socket openings 24 to press against the prongs 26 of a plug 22 inserted in the coupling socket 20, as shown in FIG. 2.

Two L-shaped input conductors 34, 35 are supported within the housing 12 by the pins 30, 31, as shown in FIG. 3, and project out through the floor 18 to form two spaced parallel socket prongs, also identified by the numbers 34, 35. The prongs 34, 35 of the coupling 10 are adapted to fit into a conventional wall socket 36, FIG. 1, in the same manner as would the conventional plug 22.

Within the housing 12, the input prong 35 is continuously connected electrically to the socket outlet conductor 29. As shown, adjacent ends of the conductors 35 and 29 are stacked together in electrical contact with each other on the common anchor pin 31 which is suitably insulated from both conductors 29 and 35.

The other prong 34 of the coupling 10 is controllably connected to the other socket output conductor 28 by means of a delayed action switch 38, FIGS. 2 and 4, and also by means of a jumper switch 40 in parallel with the delayed action switch 38.

The delayed action switch 38 comprises an L-shaped conductor 42 which lies flat on the inner surface of the floor 18 and has one end anchored to the pin 30 and stacked in contact with the inner end of the prong 34, so that the conductor 42 is continuously connected electrically with the prong 34. The end of the conductor 42 remote from the pin 30 supports a stationary contact 44 of the switch 38.

The contact 44 is opposed by a movable contact 46 supported by the free end of a bimetallic cantilever 48 which is supported at its other end around the pin 30. As shown in FIG. 4, the pin 30 is electrically isolated by a cylindrical insulator 50 from the conductors anchored by the pin 30. The supported or anchored end of the cantilever 48 is insulated electrically from the input prong 34 by an insulator washer 52.

The anchored end of the conductor 28 is stacked in contact with the anchored end of the cantilever 48. The

cantilever 48 itself constitutes a low resistance conductor connecting the contact 46 with the socket conductor 28.

A high temperature thermal insulator 56 is wrapped around a major portion of the cantilever 48 and serves as a core about which is wrapped a high resistance electrical heating wire 58.

One end 60 of the heating wire 58 is continuously connected to the input prong 34, as illustrated in FIG. 4. The other end 62 of the heating wire 58 is connected to the other input prong 35 by means of a normally open control switch 64, as illustrated in FIGS. 2 to 5.

When both the prongs 34, 35 are energized, closure of the control switch 64 produces a low wattage heating of the wire 58. Heat from the wire 58 penetrates through the thermal insulation 56 to effect heating of the bimetallic cantilever 48 which bends toward the conductor 42, FIG. 4, to engage the switch contact 46 with the switch contact 44. This closes the delayed action switch 38 to connect the socket output conductor 28 with the input prong 34. Since the other socket output conductor 29 is already energized, the delayed action switch 38 when closed serves to fully energize the socket 20 for supplying of power to a plug 22 which may be inserted in the socket 20.

It will be appreciated that there is a lapse of time between closing of the control switch 64 and closing of the delayed action switch 38 in the manner described. Immediate energization of the second socket conductor 28 in response to operation of a manual switch control to be referred to is provided by the previously mentioned jumper switch 40 in parallel with the delayed action switch 38.

Both the jumper switch 40 and the control switch 64 are operated by a common switch operator which, in the construction illustrated, comprises a knurled control knob 66 secured to the outer end of a shaft 68 journaled in a boss 70 on the dome 14 of the housing 12. The inner end of the shaft 68 carries a double lobed non-conducting cam 72 designed to operate both the jumper and control switches 40, 64 simultaneously.

In the preferred construction illustrated, the jumper switch 40 comprises two flexible conductors 74, 76 projecting within the dome 14 away from the floor 18 in normally spaced relation to each other and including two normally spaced opposed contacts 78, 80. The conductor 74 is anchored by the pin 30 in tightly engaged relation to the socket output conductor 28. The conductor 76 is supported by and in electrical contact with the input prong 34. The control switch 64 is also formed by two conductors 82, 84 which project within the dome 14 away from the floor 18 in generally parallel normally spaced relation to each other and which include two normally spaced opposed contacts 86, 88. The conductor 82 is anchored to the floor 18 by an insulated rivet 90 and is connected to the end 62 of the heating wire 58. The conductor 84 is anchored by the pin 31 in engaged electrical contact with the socket conductor 29.

The double lobed non-conducting control cam 72 is disposed between the two conductors 76, 82 of the switches 40, 64, whereupon rotation of the control knob 66 to the "on" position causes the cam 72 to move the conductor 76 toward the conductor 74 to close the switch 40 and to move the conductor 82 toward the conductor 84 to close the switch 64.

Assuming that the coupling 10 is plugged into a socket 36 and that a light 92, FIG. 1, is connected by a plug 22 with the socket 20, rotation of the control knob 66 to its "on" position effects an immediate energization of the light 92 through an immediate closure of the jumper switch 40. Closure of the control switch 64 simultaneously with the jumper switch 40 starts heating of the wire 58 and effects a somewhat delayed closing of the delayed action switch 38 while the light 92 continues to burn.

Rotation of the control 66 to its "off" position opens both the jumper switch 40 and the control switch 64. This interrupts the current flow through the high resistance low wattage heater wire 58. However, the bimetallic cantilever 48 does not cool immediately and holds the contact 46 in engagement with the contact 44 to continue energization of the light 92 through the delayed action switch 38. Moreover, the time required for the bimetallic element 48 to cool and open the switch 38 to turn out the light 92 is extended by the thermal insulation provided by the insulator 56 covering that portion of the cantilever most directly heated by the wire 58. However, the cantilever 48 does cool and opens the delayed action switch 38 after a period of time which can be predetermined to have the desired reasonable value. It will be appreciated that the time required for the switch 38 to open after the control 66 has been operated can be changed by varying the amount of insulation 56 provided for the cantilever and through other changes in dimensions, etc., which can affect the thermal value and physical responsiveness of the parts. The bimetallic cantilever 48, which moves the contact 46 into and out of engagement with the contact 44, can be accurately described as a "thermal actuator" for the movable contact 46. The inbuilt physical character of the cantilever 48 which causes the free end of the cantilever supporting the contact 46 to move downwardly with reference to FIG. 4, upon heating of the cantilever and which causes the free end of the cantilever to move upwardly upon cooling of the cantilever can be accurately described as the "thermal polarity" of the cantilever or actuator 48. The physical relationship of the parts and the thermal polarity of the thermal actuator 48 are such that the actuator upon being heated engages or closes the contacts 44, 46 and upon cooling, opens the contacts 44, 46.

In the modified construction illustrated in FIGS. 6 and 7, component elements similar to those in the construction just described are identified with the same reference numbers with the addition of the suffix "a." The switching plug 10a of FIGS. 6 and 7 is simplified in relation to the coupling 10 previously described by elimination of the socket 20 of the coupling 10, FIG. 1, and replacement of this socket with two outlet wires 96, 98, FIG. 7, which together form an electrical outlet cord 100. The construction of the dome 14a is simplified by formation of a simple cord opening 102 in place of a plug socket. The wire 96 is connected to the output conductor 74a of the jumper switch 40a and the output conductor wire 98 is connected to the energized input conductor 84a of the control switch 64a.

In another modified embodiment shown in FIGS. 8 and 9, component elements similar to those of the embodiment illustrated in FIGS. 6 and 7 are identified with the same reference numbers with the use of the suffix "b." In this form, the cam 72b operated by the knob 66b to control the switches 40b and 64b is modified to be only a single lobed cam, rather than a double lobed cam, so that the cam 72b operates to close the switches 40b and 64b one at a time rather than simultaneously.

This gives the user the option of closing only the jumper switch 40b which serves to immediately energize the output cord 100b and to subsequently deenergize the output cord 100b immediately upon turning of the control 66b to its "off" position. In the alternative, the user can turn the control 66b to close only the control switch 64b. This produces a delayed energization of the cord 100b and subsequently effects a delayed deenergization of the cord 100b upon turning of the control 66b to its "off" position. Thus, this embodiment provides the user with the option of determining whether or not there will be a delay in the deenergization of the main circuit when the control is turned to its "off" position.

The invention is claimed as follows:

1. A delayed action plug-socket switch comprising, in combination, a housing including a generally hollow dome defining an opening thereinto and a floor interfitting with said dome to close said opening thereinto, both said dome and said floor being formed of insulating materials, said dome including a socket integrally formed on one side of said dome and defining two prong receiv-

ing openings, first and second socket outlet conductors mounted in said housing in inward aligned relation to said respective prong receiving openings, first and second electrical plug prongs supported on said floor and projecting therefrom away from said dome, means in said housing connecting said first prong to said first socket conductor, first and second delayed action switch contacts disposed within said housing, a thermal actuator disposed within said housing and being connected to said second contact to move said second contact into and out of engagement with said first contact upon heating and cooling of the actuator, one of said contacts being connected electrically to said second prong and the other of said contacts being connected electrically to said second socket conductor, a thermal insulator disposed within said housing in closely adjacent thermally insulating relation to said actuator to delay cooling of the actuator, an electrical heater disposed within said housing in proximate heat transferring relation to said actuator and having two energizing terminals one of which is connected to one of said prongs, a normally open control switch disposed within said housing and connecting the other one of said heater terminals to the other one of said prongs, a normally open jumper switch disposed within said housing and connecting said second prong and said second socket conductor, and manual operating means extending from outside said housing into the housing and operatively coacting with said control switch and said jumper switch within the housing to effect manual opening and closing of said control switch and said jumper switch.

2. A delayed action plug-socket switch comprising, in combination, a housing including a generally hollow dome defining an opening thereinto and a floor interfiting with said dome to close said opening thereinto, both said dome and said floor being formed of insulating materials, said dome including a socket integrally formed on one side of said dome and defining two prong receiving openings, first and second socket outlet conductors mounted in said housing in inward aligned relation to said respective socket openings, first and second electrical plug prongs supported on said floor and projecting therefrom away from said dome, means in said housing connecting said first prong to said first socket conductor, first and second delayed action switch contacts disposed within said housing, a bimetallic cantilever in said housing supporting said second contact and being positioned to engage said second contact with said first contact upon heating of the cantilever and to disengage said second contact from said first contact upon cooling of the cantilever, one of said contacts being connected electrically to said second prong and the other of said contacts being connected electrically to said second socket conductor, a thermal insulator wrapped around said cantilever in thermally insulating relation thereto, a high resistance resistor wire wrapped around said thermal insulator to heat said cantilever, one end of said resistor wire being connected to one of said prongs, a normally open control switch connecting the other end of said resistor wire to the other of said prongs, said control switch comprising two normally spaced conductors projecting from said floor within said dome and including two normally spaced contacts, a normally open jumper switch connecting said second prong and said second socket conductor and comprising two normally spaced conductors projecting from said floor within said dome and including two normally spaced contacts, and a switch operator movably supported on said housing for effecting relative movement toward and away from each other of the two conductors of each of said control and jumper switches.

3. A manually controlled switch for effecting a delayed cutting off of electrical power, comprising, in combination, first and second input conductors, a first output conductor connected to said first input conductor, a second output conductor, first and second delayed action switch contacts,

thermal actuating means connected to said second contact to move said second contact into and out of engagement with said first contact, said thermal actuating means being responsive to heating and cooling of the thermal actuating means to move in opposite directions having a predetermined thermal polarity, said thermal actuating means being physically positioned in relation to said first and second contacts and in relation to said thermal polarity of the actuating means to move said second contact into engagement with said first contact upon heating of the actuating means and to move said second contact out of engagement with said first contact upon cooling of the actuating means, one of said contacts being connected to said second input conductor and the other of said contacts being connected to said second output conductor, said thermal actuating means including electrical heating means therefor, a manual control switch; means connecting said manual control switch and said electrical heating means in series between said first and second input conductors to effect, when said manual control switch is closed, energization of said heating means and heating of said thermal actuating means which moves said second contact into engagement with said first contact thereby connecting said second output conductor with said second input conductor and to effect, in response to opening of said manual control switch, deenergization of said heating means causing said thermal actuating means to cool and subsequently move said second contact out of engagement with said first contact thereby disconnecting said second output conductor from said second input conductor; a manually actuated jumper switch connected between said second input conductor and said second output conductor to effect energization of the latter independently of said contacts, and a common manual actuator connected to operate both said control and jumper switches.

4. A delayed action plug-socket switch comprising, in combination, a housing including means forming a socket defining two prong receiving openings, first and second socket conductors supported within said housing in inward alignment with said respective openings, first and second electrical plug prongs supported on said housing and projecting therefrom in generally parallel spaced relation to each other, means within said housing connecting said first prong electrically with said first socket conductor, first and second delayed action switch contacts disposed within said housing, thermal actuating means disposed within said housing and being connected to said second contact to move said second contact into and out of engagement with said first contact, said thermal actuating means being responsive to heating and cooling of the thermal actuating means to move in opposite directions having a predetermined thermal polarity, said thermal actuating means being physically positioned in relation to said first and second contacts and in relation to said thermal polarity of the actuating means to move said second contact into engagement with said first contact upon heating of the actuating means and to move said second contact out of engagement with said first contact upon cooling of the actuating means, electrical heating means disposed in said housing in proximate heat transferring relation to said thermal actuating means to heat the latter, one of said contacts being connected to the said second prong and the other of said contacts being connected to said second socket conductor, a manual control switch disposed within said housing, a manual actuator extending from outside said housing into the housing and coacting with said control switch to operate the latter; and means connecting said manual control switch and said electrical heating means in series between said first and second plug prongs to effect, when said manual control switch is closed, energization of said heating means and heating of said thermal actuating means which moves said second contact into engagement with said first contact thereby connecting said second socket conductor with said second plug prong and to effect, in response to opening of said manual control switch, deener-

gization of said heating means enabling said thermal actuating means to cool and subsequently move said second contact out of engagement with said first contact thereby disconnecting said second socket conductor from said second plug prong.

5. A delayed action plug-socket switch comprising, in combination, a housing including means forming a socket defining two prong receiving openings, first and second socket conductors supported within said housing in inward alignment with said respective openings, first and second electrically conducting plug prongs supported on said housing and projecting therefrom in generally parallel spaced relation to each other, means within said housing connecting said first prong electrically with said first socket conductor, first and second delayed action switch contacts disposed within said housing, a bimetallic cantilever supporting said second contact and being constructed and positioned to engage said second contact with said first contact upon heating of said cantilever and to disengage said second contact from said first contact upon cooling of said cantilever, one of said contacts being connected electrically to said second prong and the other of said contacts being connected electrically to said second socket conductor, a high resistance resistor disposed within said housing in heat transferring relation to said bimetallic cantilever, said resistor being connected at one electrical end thereof to one of said prongs, a normally open control switch connecting the other electrical end of said resistor to the other of said prongs and being disposed within said housing, a thermal insulator disposed within said housing and being located in closely adjacent thermally insulating relation to a portion of said cantilever which is heated by said resistor to delay cooling of said cantilever, a normally open jumper switch contained within said housing and being connected between said second prong and said second socket conductor, and a movable switch operator extending from outside said housing into said housing and operatively coacting with said control switch and said jumper switch to effect manual opening and closing of the control and jumper switches.

6. A delayed action plug-socket switch comprising, in combination, a housing including means forming a socket defining two prong receiving openings, first and second socket conductors supported within said housing in inward alignment with said respective openings, first and second electrical plug prongs supported on said housing and projecting therefrom in generally parallel spaced relation to each other, means within said housing connecting said first prong electrically with said first socket conductor, first and second delayed action switch contacts disposed within said housing, a bimetallic cantilever disposed within said housing and movably supporting said second contact, said bimetallic cantilever being thermally polarized and positioned to move said second contact into engagement with said first contact upon heating of said cantilever and to move said second contact out of engagement with said first contact upon cooling of said cantilever, one of said contacts being connected electrically to said second prong and the other of said contacts being connected electrically to said second socket conductor, a resistor disposed within

5 said housing in proximate heat transferring relation to said bimetallic cantilever, said resistor being connected at one electrical end thereof to one of said prongs, a normally open control switch connecting the other electrical end of said resistor to the other of said prongs and being disposed within said housing, a thermal insulator disposed within said housing and being located in closely adjacent thermally insulating relation to a portion of said cantilever which is heated by said resistor to delay cooling of said cantilever, a normally open jumper switch contained within said housing and being connected between said second prong and said second socket conductor, and a movable switch operator extending from outside said housing into said housing and operatively coacting with said control switch and said jumper switch to effect manual opening and closing of the control and jumper switches.

7. A delayed action switch comprising, in combination, a first input conductor, a first output conductor, a first switch contact connected to one of said conductors, a second switch contact connected to the other of said conductors, thermal actuating means connecting to said second contact to move said second contact into and out of engagement with said first contact, said thermal actuating means being responsive to heating and cooling of the thermal actuating means to move in opposite directions having a predetermined thermal polarity, said thermal actuating means being physically positioned in relation to said first and second contacts and in relation to said thermal polarity of the actuating means to move said second contact into engagement with said first contact upon heating of the actuating means and to move said second contact out of engagement with said first contact upon cooling of the actuating means, electrical heating means disposed in proximate heat transferring relation to said thermal actuating means to heat the latter, a second input conductor, a second output conductor connected to said second input conductor, a manual control switch; and means connecting said manual control switch and said electrical heating means in series between said first and second input conductors to effect, when said manual control switch is closed, energization of said heating means and heating of said thermal actuating means which moves said second contact into engagement with said first contact thereby connecting said first output conductor with said 20 first input conductor and to effect, in response to opening of said manual control switch, deenergization of said heating means causing said thermal actuating means to cool and subsequently move said second contact out of engagement with said first contact thereby disconnecting said first output conductor from said first input conductor.

8. A delayed action switch comprising, in combination, a housing, first and second output conductors supported within said housing, first and second electrically conducting plug prongs supported on said housing and projecting therefrom in generally parallel spaced relation to each other, means within said housing connecting said first prong electrically with said first output conductor, first and second delayed action switch contacts disposed within said housing, thermal actuating means disposed within said housing and coacting with said second contact to move said second contact into engagement with said first contact upon heating of said actuating means and to move said second contact out of engagement with said first contact upon cooling of said actuating means, one of said contacts being connected electrically to said second prong and the other of said contacts being connected electrically to said second output conductor, said thermal actuating means including electrical heating means having two energizing terminals one of which is connected to one of said prongs, 30 a normally open control switch contained within said housing and comprising first and second conductors cantilevering in spaced opposed relation to each other and being connected respectively with the prong other than said one prong and with the heating means terminal other than said one terminal, a normally open jumper switch

contained within said housing and comprising third and fourth conductors connected respectively to said second prong and said second output conductor and cantilevering in spaced opposed relation to each other, a single switch operator movably disposed in said housing in operatively coacting relation to said first and second conductors of said control switch and in operatively coacting relation to said third and fourth conductors of said jumper switch, and a manual switch actuator extending from outside said housing into said housing and coacting with said switch operator for manually actuating said operator to close and open said control switch by effecting relative movement of said first and second switch conductors thereof toward and away from each other and to effect closing and open-

5

10

ing of said jumper switch by moving said third and control switch and said jumper switch to close and open each switch by electrically connecting and disconnecting said conductors thereof.
